ELECTRIC CIRCUIT CONTROL MEANS

Lewis R. Runaldue, Pittsfield, Mass., assignor to
General Electric Company, a corporation of
New York

Application April 13, 1938, Serial No. 201,799

10 Claims. (Cl. 175—320)

My invention relates to electric circuit control means and more particularly to electric circuit control means energized from alternating or periodically varying current supply means.

5 In the control and regulation of electric circuits, apparatus and devices, it is common practice to employ an electroresponsive device such as a relay with a movable armature or plunger operative to different positions, depending upon 10 the variation of the controlled condition above or below a predetermined value. Relays of this type, unless specially constructed, exhibit a different impedance for different operating conditions such as for different positions of the armature or plunger when operated from an alternating current circuit. It is desirable in certain 15 applications to maintain the impedance of the electro-responsive device substantially constant for any operating position or condition. I have 20 found that a condition of substantially constant impedance and power factor is particularly desirable in connection with so-called nonlinear resonant circuit control and regulating devices. One of the well known forms of the nonlinear 25 resonant circuit relays comprises a so-called series type nonlinear resonant circuit wherein a closed core inductance element, a capacitance element and a resistance element are connected in series relation with a relay connected to be 30 energized across one of the elements, such as the capacitance, of the nonlinear resonant circuit. In this type of circuit the voltage at which the current of the nonlinear circuit changes abruptly to a higher value and hence causes the relay to 35 pick up is known as the "resonant" or "pick-up" voltage and the voltage at which the current of the nonlinear circuit abruptly decreases to a lower value and hence causes the relay to drop out is known as the "dissonant" or "drop-out" 40 voltage. The difference between the pick-up and drop-out voltages is known as the "holding effect". It has been found in practice that in certain 45 applications of the nonlinear resonant circuit relays, certain circuit conditions cause a variation in the holding effect which is undesirable particularly in many regulating applications.

It is an object of my invention to provide an improved electric circuit control means.

It is another object of my invention to provide 50 an improved electric circuit control means of the nonlinear resonant type.

It is a further object of my invention to provide a nonlinear resonant relay which shall have a substantially constant holding effect.

55 It is a still further object of my invention to

provide an improved arrangement of a plurality of nonlinear resonant relays wherein the difference between the voltages at which the respective relays operate may be maintained substantially constant.

In accordance with the illustrated embodiments of my invention, I provide means whereby the impedance and the power factor of the relay circuit energized from the nonlinear resonant circuit are maintained substantially constant. One of the illustrated embodiments shows a corrective inductance associated with the relay coil, while another form shows how my invention may be carried into effect with a capacitance.

My invention will be better understood by reference to the following description taken in connection with the accompanying drawing and its scope will be pointed out in the appended claims.

In the drawing, Fig. 1 is a diagrammatic illustration of an embodiment of my invention wherein a corrective inductance is used; Fig. 2 shows a modification of the arrangement illustrated in Fig. 1 wherein a corrective capacitance is used, and Fig. 3 is a diagrammatic illustration of an embodiment of my invention as applied to a plurality of relays in a regulating circuit.

Referring to Fig. 1 of the drawing, I have shown a nonlinear resonant circuit of the series type comprising a closed core saturable inductance 10, a fixed resistance 11, a variable resistance 12, and a capacitance 13 all connected in series to be energized from a suitable source of alternating current represented very diagrammatically as an alternating current generator 14. An electroresponsive device, illustrated as an electromagnetic relay 15, is connected to be energized from the nonlinear resonant circuit and preferably in accordance with the voltage across the capacitance element 13. The relay 15 is shown, by way of example, as comprising an operating coil 16 provided with a movable core 17, although it will be obvious to those skilled in the art that my invention is not limited to a particular type of relay and is equally applicable whether core movement is involved or some form of fixed core provided with a movable armature. In its broader aspects my invention is applicable for use in connection with any type of nonlinear resonant circuit of the series, parallel, or series-parallel type, etc., and with various types of electro-responsive devices which exhibit a different impedance in the operated and nonoperated positions. The relay 15 is provided with circuit controlling means which are illustrated as a pair of contacts 18 and 19 arranged to control the energization of a 55

control circuit 20 which may be energized from any suitable source, which, as illustrated, may be the source 14.

One circuit condition which causes a variation 5 in the holding effect of a relay energized from a nonlinear resonant circuit is a variation in the wave shape of the applied voltage. In accordance with my invention, I maintain the impedance and power factor of the relay circuit 10 substantially constant so that the pick-up and drop-out voltages of the relay will be affected equally by variations in wave shape and hence the holding effect will be maintained substantially constant. In the form of relay shown in 15 Fig. 1 when the core 17 is pulled into its winding 16, the impedance of the relay is higher than when the core is in its drop-out position. In order to keep the impedance and the power factor, both in magnitude and sign, of the relay circuit 20 substantially constant, I provide a compensating circuit comprising a resistance 21 and an inductance element 22 to be connected in parallel relation with the relay 16 when the relay moves to its pick-up position, so that the impedance and power factor of the relay circuit are 25 substantially the same in the pick-up position of the relay as in the drop-out position. Obviously, no particular value of the compensating impedance can be specified for all cases since the various types of relays will vary widely as to impedance values in the pick-up and drop-out positions, respectively. However, with a nonlinear 30 resonant relay now used commercially, I have found that a compensating circuit comprising 35 110 henrys in series with 1000 ohms of resistance compensates satisfactorily for the changes in impedance and power factor of a commercial relay used in connection with distribution regulators wherein the relay impedance increase in the pick-up position is of the order of five times the impedance in the drop-out position. In the embodiment illustrated in Fig. 1, the compensating circuit 21-22 is connected automatically in parallel with the relay coil 16 through the control 40 circuit contact 18 of the relay 15. However, it will occur to those skilled in the art that the connection of the compensating circuit may be effected in a number of ways, such as by separate sets of contacts as shown in other embodiments 45 of my invention, without departing from my invention in its broader aspects.

In Fig. 2 I have shown another embodiment 50 of my invention which utilizes a capacitance compensating means and in which the impedance 55 of the relay circuit in the drop-out position of the relay is maintained at the same value as the impedance of the relay in its pick-up or closed position. In this illustrated embodiment of my invention, elements corresponding to those of Fig. 1 have been assigned the same reference numerals. The compensating circuit in this arrangement 60 comprises a capacitance 23 which is connected through separate contacts 24 of relay 15 in parallel relation with the relay coil 16 in the drop-out position of the relay and automatically disconnected when the relay is in its pick-up position. In commercial applications it may be desirable to include a resistor 23' in series relation 65 with the capacitor 23 for purposes of adjustment. The main contacts 18 and 19 of relay 15 control the energization of the control circuit 20, but in this case the control circuit is arranged to be energized from a separate source 25. However, 70 it is immaterial, so far as my invention is con-

cerned, what source is utilized to energize the control circuit 20.

In Fig. 3 I have shown an embodiment of my invention in connection with each resonant relay of a plurality of relays so that a substantially 5 constant regulating band width may be maintained in spite of changes in wave shape of the voltage applied to the respective resonant relay circuits. In this arrangement the circuit 26 represents diagrammatically an electric circuit, 10 such as a feeder circuit, connected to be energized from a source 27. Load devices are schematically indicated by a resistance 28, inductance 29, and capacitance 30 connected to be energized from circuit 26. A regulator 31, which is to be 15 taken as illustrative of any of the known types of regulators, whether of the rheostatic, inductive or step type, is diagrammatically represented as a single phase induction regulator connected to the circuit 26 in the well known manner and 20 arranged for operation by any convenient electric means shown as a reversible motor 32. The motor 32 is illustrated, by way of example, as of the capacitor type having two controlling circuits 33 and 34 for selectively determining the direction of rotation of the motor and a common return conductor 35. The motor 32 is arranged to operate the regulator 31 through suitable gearing 36 and is connected to be energized from any convenient source, such as from the circuit 26 30 through transformer 37. The return conductor 35 is connected permanently to one side of the secondary winding of transformer 37, while the conductors 33 and 34 are arranged to be selectively connected to the other side of the secondary 35 winding of transformer 37 in accordance with the operation of circuit control means 38.

The circuit control means 38 includes a pair of relays 39 and 40. Relay 39 may comprise an operating winding 41 having a movable core 40 member 42 for closing a pair of contacts 43 in the control circuit conductor 38 when the relay winding 41 is deenergized below a predetermined value or in its drop-out position. This relay is provided with an inductance compensating circuit, as 45 shown in Fig. 1 of the drawing, which includes a resistance 44 and an inductance 45 arranged to be connected in parallel with the operating winding 41 through relay contacts 46 when relay 39 is in its pick-up position. Similarly, relay 40 50 may comprise an operating winding 47 having a movable core member 48 for closing a pair of contacts 49 when the winding 47 is deenergized below a predetermined value, or the relay is in its drop-out position, and for simultaneously 55 opening contacts 49 and closing contacts 50 in the control circuit conductor 34 when the relay 40 is in its pick-up position. The relay 40 is similarly provided with an inductance compensating circuit comprising the resistance 51, and inductance 60 52 which are arranged to be connected in parallel with the relay winding 47 through relay contacts 53 when the relay moves to its pick-up position. The contacts 43 of relay 39 when closed complete the circuit including conductors 38 and 39 if contacts 49 of relay 40 are closed for operating the motor 32 in a direction to raise the voltage of circuit 26 and hence relay 39 may be referred to as the "raise" relay. The contacts 50 of relay 40 when closed complete the circuit including 65 conductors 34 and 35 for operating motor 32 in a direction to lower the voltage of circuit 26 and hence relay 40 may be referred to as the "lower" relay. Since the "lower" relay must be in its drop-out position in order for the "raise" relay 70 75

to complete the raising circuit, an electrical interlock is thereby provided so as to prevent closing of both motor control circuits at the same time.

5 Relays 39 and 40 are each controlled by a different nonlinear resonant circuit indicated generally by R and L, respectively. The nonlinear resonant circuit R, for controlling relay 39, is shown as a series type circuit comprising a capacitance 54, a saturable inductance 55 and a resistance 56. Both the inductance and resistance may be made adjustable, as shown, in order to adjust the holding effect of the relay. The inductance may be made adjustable by various 10 known means and, by way of example, I have shown a rotatable core member 57 operating in a gap in the core and so shaped, such as a segment of a cylinder as shown, that upon rotation the reluctance of the core may be changed to 15 vary the inductance of the inductance element 55. The drop-out or dissonant voltage of the relay is adjusted primarily by adjusting the resistance 56, whereas the pick-up or resonant voltage is adjusted by adjusting the inductance element 55. The winding 41 of relay 39 is connected to be energized in accordance with the voltage of capacitance 54. The nonlinear resonant circuit L is similarly shown as comprising a series type of circuit including a capacitance 58, an inductance 59 and a 20 resistance 60. The inductance element 58 is made adjustable in a manner similar to the inductance element 55 by means of the core reluctance varying means 61.

The nonlinear resonant circuits R and L are 25 connected to be energized from the circuit 26 in any desired manner in order to be responsive to the condition to be controlled, and I have shown, by way of example, a known arrangement which comprises an auto-transformer 62 having adjustable taps 63 and 64, respectively, connected to the different conductors of circuit 26. One side of the nonlinear resonant circuits may be permanently connected to some appropriate point in the transformer 62 and the other side of each of 30 the nonlinear circuits may be connected, respectively, through adjustable connecting means 65 and 66 to other points of different potentials.

In voltage regulating systems it is common practice to hold on the regulated current some 35 selected voltage such as 115 volts. Under such conditions, it is common practice to require a band of several volts between operating voltages of the "raise" and "lower" relays. This band may be, for example, 3 volts. It is also desirable 40 to have some holding effect, for example 0.5 volt, to insure positive action of the mechanism. The adjustment of the band width may be obtained by adjusting the dissonant or drop-out voltage of the raise relay 39, for example by adjusting 45 the resistance 56 of the raise nonlinear resonant circuit. The holding effect of relay 39 is adjusted by adjusting the resonant or pick-up voltage by means of the inductance adjusting means 57. The lower relay 40 is adjusted by means of the 50 inductance varying means 61 so that its resonant or pick-up voltage will lower the voltage when the relay pulls in. The dissonant or drop-out voltage of relay 40 may be adjusted by means of the resistance 60 to give the proper holding effect. 55 Thus with the holding effect of the respective relays adjusted and the band width adjusted, my compensating circuit, as employed with each relay, will maintain the holding effect of each relay substantially constant and will at the same time 60 maintain the band width constant in spite of

variations in wave form. Although the pick-up and drop-out voltages of the respective relays may vary, the difference between these voltages for any one relay, or the difference between the drop-out voltage of one relay and the pick-up voltage of another, may be maintained substantially constant.

The general system shown in Fig. 3 and the operation thereof is known in the art and only a brief description thereof, sufficient to explain the 10 manner in which my compensating means operates in such a system, is believed to be necessary. Let it be assumed that it is desired to hold 115 volts on circuit 26 and that the "raise" relay 39 is adjusted to have a drop-out voltage of 113.5 15 volts and a holding effect of 0.5 volt and hence a pick-up voltage of 114 volts. If the band width is to be 3 volts, then the lower relay adjustment must pick up at 116.5 volts with a holding effect of 0.5 volt and will drop out at 116 volts. If the 20 voltage of circuit 26 drops to 113.5 volts, the relay 39 will drop out and close an energizing circuit through its contacts 43 and circuit 33 to cause motor 32 to operate in such a direction as to increase the voltage of circuit 26. When the voltage of circuit 26 reaches the assumed pick-up value of 114 volts, relay 39 picks up and the regulator brings the regulated voltage up to the nominal value of 115 volts. When relay 39 picks up it closes its contacts 46 to connect the compensating circuit 44-45 in parallel with the relay winding 41 and thereby keeps the impedance of the relay circuit at the same value as for the drop-out position of the relay and hence maintains the holding effect constant. If now the 35 voltage of circuit 26 increases to the pick-up value of relay 40, which is assumed to be 116.5 volts, relay 40 picks up, closes its contacts 50 in control conductor 34 to cause motor 32 to operate in such a direction as to decrease the voltage of circuit 26. At the same time, the compensating circuit 51-52 is connected in parallel with the relay winding 47 so that the impedance of this relay circuit is kept at the same value as for the drop-out position of the relay. When the voltage of circuit 26 decreases to the assumed drop-out voltage of 116 volts, relay 40 drops out and the regulator brings the voltage down to the normal value of 115 volts. Since the holding effect of the respective relays is maintained constant, then the band width will therefore be maintained constant even though there may be slight simultaneous and equal variations in the pick-up and drop-out voltages of the respective relays. For example, if the drop-out voltage of the raise relay 45 changes to 114 volts, then the pick-up voltage of relay 40 will increase a like amount to 117 volts and the band width will still remain 3 volts.

While I have shown and described particular embodiments of my invention, it will occur to those skilled in the art that various changes and modifications may be made without departing from my invention and I, therefore, aim in the appended claims to cover all such changes and modifications as fall within the true spirit and scope of my invention.

What I claim as new and desire to secure by Letters Patent of the United States is:

1. In combination, an electric circuit, a branch circuit including an electroresponsive device connected to be energized from said circuit and normally having different impedance values for different operating conditions of said electroresponsive device, and means operative in accordance with an operating condition of said electro- 70

- responsive device for varying the impedance of said branch circuit for maintaining the impedance of said branch circuit substantially constant for different predetermined operating conditions of said electroresponsive device.
2. In combination, an electric circuit, a branch circuit connected to be energized from said electric circuit and including an electromagnetic relay having two operating conditions and normally having a different impedance in one operating condition than in the other, and means operative in accordance with the operation of said relay from one operating condition to the other for maintaining the impedance of said branch circuit substantially the same for either operating condition of said relay.
3. In combination, an alternating current circuit, an electromagnetic relay connected to be energized from said circuit, said relay having a magnetic element movable from one operating position to another and normally having a higher impedance for one position of said magnetic element than the other, a branch circuit comprising an inductance element having such a value when connected in parallel relation with said relay at its normally high impedance position as to render the impedance and power factor of said branch circuit substantially the same as for said other position of said magnetic element, and circuit control means operated by said relay for connecting said inductance element in parallel relation with said relay when in its higher impedance position.
4. In combination, an alternating current circuit, an electromagnetic relay connected to be energized from said circuit, said relay having a magnetic element movable from one operating position to the other and normally having a relatively high impedance for one position of said magnetic element and a relatively low impedance for the other position of said magnetic element, a branch circuit comprising a capacitance element normally connected in parallel relation with said relay in its low impedance position and having such a value as to render the impedance and power factor of said branch circuit substantially the same as for the high impedance position of said magnetic element, and circuit control means operated by said relay for disconnecting said capacitance when said magnetic element moves to its high impedance position.
5. In combination, a nonlinear resonant circuit comprising a saturable inductance and a capacitance, a branch circuit connected to be energized from said nonlinear circuit and including a relay normally having relatively high and low impedance operating positions, a second branch circuit including an impedance having such a value of impedance when connected to said first branch circuit as to render the impedance and power factor of said first branch circuit substantially the same in both operating positions of said relay, and means controlled by said relay for connecting said second branch circuit to said first branch circuit in one of the operating positions of said relay.
6. In combination, a nonlinear resonant circuit comprising a saturable inductance and a capacitance, a branch circuit connected to be energized from said nonlinear circuit and including a relay having normally relatively high and low impedance operating positions, a second branch circuit comprising an inductance element having such a value when connected in parallel relation with said relay in its high impedance position as to render the impedance and power factor of said branch circuits substantially the same as for the low impedance position of said relay, and switching means operative in accordance with the position of said relay for connecting said second branch circuit in parallel relation with said first branch circuit when said relay is in its normally high impedance position.
7. In combination, a nonlinear resonant circuit comprising a saturable inductance and a capacitance, a branch circuit connected to be energized from said nonlinear circuit and including a relay having normally relatively high and low impedance operating positions, a second branch circuit comprising a capacitor connected in parallel relation with said first branch circuit when said relay is in its low impedance position and having such a value of capacitance as to render the impedance and power factor of such branch circuits substantially the same as for said high impedance position of said relay, and switching means operative in accordance with the portion of said relay for disconnecting said second branch circuit from said first branch circuit when said relay is in its high impedance positions.
8. In combination, an alternating current circuit, an electroresponsive device, a pair of electromagnetic relays each being connected to be energized from said circuit and arranged for controlling said electroresponsive device, said relays each having two operating positions and each normally having relatively high and low impedance positions, means for adjusting the holding effect of each relay, means for adjusting the band width of said relays, impedance means in operative connection with each relay, and circuit controlling means for changing the connection of said impedance means with its associated relay for maintaining the impedance and power factor of each relay circuit substantially the same in either of its operating positions so as to maintain the band width of said relays substantially constant.
9. In combination, an alternating current circuit, an electroresponsive device, a pair of nonlinear resonant circuits connected to be energized from said circuit, a pair of electromagnetic relays each having normally relatively high and low impedance operating positions and each connected to be energized from a different nonlinear resonant circuit, said relays being arranged for controlling said electroresponsive device, means for adjusting each nonlinear resonant circuit for adjusting the holding effect of the relay associated therewith, means for adjusting each nonlinear resonant circuit for adjusting the band width of said relays, a pair of branch circuits each including an impedance element having such a value relative to the value of its associated relay as to render the impedance and power factor of each relay substantially the same for either of its operating positions, and switching means operated by each relay for changing the connection of its associated branch circuit when said relay changes from one operating position to the other so as to maintain the band width of said relays substantially constant.
10. In combination, an alternating current circuit, an electroresponsive device, a pair of nonlinear resonant circuits connected to be energized from said circuit, a pair of electromagnetic relays each having a normally relatively high impedance in its pick-up position and a relatively low impedance in its drop-out position, each of said relays being connected to be energized from a different

nonlinear resonant circuit, said relays being arranged for controlling said electroresponsive device, means for adjusting each nonlinear resonant circuit for adjusting the holding effect of the relay associated therewith, means for adjusting each nonlinear resonant circuit for adjusting the band width of said relays, a pair of branch circuits each including an inductance element having such a value when connected in parallel relation with its associated relay in its pick-up

position as to render the impedance and power factor of said relay and its associated branch circuit substantially the same as for the drop-out position of said relay, and switching means operated by each relay for connecting its associated branch circuit in parallel relation therewith when each relay is in its pick-up position so as to maintain the band width of said relays substantially constant. 5

LEWIS R. RUNALDUE. 10
